HERMAN J. GREINERT

Ch. Farlin Attorney

Patented Feb. 27, 1923.

UNITED STATES PATENT OFFICE.

HERMAN JOSEPH GREINERT, OF BUFFALO, NEW YORK.

DETONATING TOY.

Application filed November 8, 1921. Serial No. 513,777.

To all whom it may concern:

Be it known that I, HERMAN J. GREINERT, a citizen of the United States, residing at Buffalo, in the county of Erie and State of New York, have invented certain new and useful Improvements in Detonating Toys, of which the following is a specification.

This invention relates to detonating toys, and is an improvement on the construction 10 shown in my prior Patent No. 694,633.

In the said patent, there is shown a detonating toy comprising a traction wheel having concentric flanges forming cartridge receiving chambers, a spring pressed hammer, 15 and cams formed on said wheel to raise the hammers and cause them to strike cartridges arranged in openings in said cartridge receiving members.

An object of the present invention is the 20 provision of a toy of this character having a hammer of improved construction.

A further object is the provision of means for retaining the cartridges in the cartridge receiving chambers.

The cartridge receiving chambers, being 25 formed in a flange on the traction wheel, revolve with said wheel and are liable to become displaced. In the present invention, I employ a disk or plate arranged at one 30 side of the wheel provided with fingers or projecting portions adapted to overlie the periphery of the flange and retain the cartridges in position.

In the accompanying drawings, I have 35 shown one embodiment of the invention. In this showing:

Figure 1 is a side elevation,

Figure 2 is a plan view,

Figure 3 is a vertical section on line 3—3 40 of Figure 1, and,

Figure 4 is a similar view on line 4—4 of Figure 1.

Referring to the drawings, the reference 45 numeral 1 designates a wheel mounted on a pin or axle 2. An arm 3 is secured to the axle projecting therefrom. The end of this arm is adapted to be received in a handle 4.

The traction wheel is provided with a concentric flange 5 having a plurality of radial 50 openings 6 for the reception of cartridges 7. It will be apparent that as the wheel revolves, there is a possibility of the cartridges falling from the openings 6 which form the cartridge receiving chambers. A cartridge 55 retainer is provided to prevent accidental displacement of the cartridges. As shown,

it comprises a disk 8 which is arranged on the axle or pin and which is of substantially the same size as the flange 2. The outer edge of the disk is provided with a plurality 60 of projections 9 extending over the periphery of the flange and adapted to engage a portion of the cartridge as shown in Figures 2 and 3. The face of the disk is provided with projecting lugs 10 to permit it to be re- 65 volved.

The arm 3 is provided with a bracket 11 and a hammer 12 is pivoted on this bracket, as at 13. The hammer moves in an elongated slot 14, formed in a guide plate 15, 70 and is normally retained in lowered position by means of a spring 16. As shown, one end of the spring is secured to the hammer, as at 17, and the other end is secured to a flange 18 formed on an arm 19, depending from the 75 arm 3. The hammer is raised against the tension of the spring by means of cams 20 formed on the traction wheel 1.

The operation of the device is as follows:

When the cartridge receiving chambers 80 are to be filled, the cartridge retainer 8 is revolved by grasping the lugs 10 to bring the projections 9 out of alignment with the openings 6 and permit insertion of the cartridges. After the cartridge receiving chambers have been filled, the cartridge retainer 85 is returned to its original position with the projections 9 engaging the faces of the cartridge. The wheel is then revolved by running it over the surface and the hammer is 90 raised by the cams 20. The end of each cam is arranged substantially in radial alignment with a cartridge receiving chamber, and as the hammer rides off the cam, it is caused to strike the cartridge by the spring 16, 95 which has been placed under tension when the hammer is raised.

It will be apparent that the provision of a cartridge retainer prevents the cartridges from becoming displaced when the wheel is 100 revolved.

It is to be understood that the form of my invention herewith shown and described is to be taken as a preferred example of the same, and that various changes in the shape, 105 size, and arrangement of parts may be resorted to without departing from the spirit of the invention or the scope of the subjoined claims.

Having described my invention, I claim: 110

1. A detonating toy comprising a wheel having a concentric flange, said flange being

provided with peripheral openings forming cartridge receiving chambers, a disk disposed adjacent said wheel, the edge of said disk being provided with projections overlying the periphery of said flange to retain the cartridges in said chambers, a hammer pivotally mounted adjacent said wheel, and means for operating said hammer.

2. A detonating toy comprising a wheel 10 having a concentric flange, said flange being provided with peripheral openings forming cartridge receiving chambers, a disk disposed adjacent said wheel, the edge of said disk being provided with projections over-

lying the periphery of said flange to retain 15 the cartridges in said chambers, the face of said disk being provided with lugs to permit the disk to be moved to inoperative position, a hammer pivotally mounted adjacent said wheel, and means for operating said 20 hammer.

In testimony whereof I affix my signature in presence of two witnesses.

HERMAN JOSEPH GREINERT.
